Nov. 7, 1933.

W. T. LEATHERDALE ET AL

1,933,862

HOLDER FOR EDIBLES AND GENERAL MERCHANDISE

Filed March 12, 1931

FIG. 1

FIG. 2

FIG. 4

FIG. 3

FIG. 5

FIG. 6

INVENTORS
W. T. Leatherdale
W. J. Wilson
BY
E. J. Fetherstonhaugh
ATTORNEY

UNITED STATES PATENT OFFICE

1,933,862

HOLDER FOR EDIBLES AND GENERAL MERCHANDISE

William Thomas Leatherdale and William Jamieson Wilson, Toronto, Ontario, Canada

Application March 12, 1931. Serial No. 521,966

1 Claim. (Cl. 217—76)

The invention relates to improvements in holders for edibles and general merchandise, as described in the present specification and shown in the accompanying drawing that forms a part 5 of the same.

The invention consists essentially of the novel features pointed out in the claim for novelty following a description containing an explanation in detail of an acceptable form of the invention.

10 The objects of the invention are to devise a holder that may be secured to the open portion of a crate or case or in another form be a complete case in itself; to construct a holder that will be ornamental in appearance and will add as an 15 embellishment in the display of the shopkeeper and others; to minimize waste in floor space and utilize the unused space in shop windows and in the stores; to display fruit, vegetables and general merchandise in an appetizing and attractive 20 manner; to construct a holder that can be easily attached or removed to various crates or cases; and generally to provide a holder that will be durable in construction, comparatively cheap to manufacture and efficient for the purpose set 25 forth.

In the drawing, Figure 1 is a front elevational view of the holder in the form of a case.

Figure 2 is a perspective view of the holder in the form of a case.

30 Figure 3 is a vertical sectional view of the holder taken on the lines 3—3 in Figure 2.

Figure 4 is a front elevational view of the holder as an attachment.

Figure 5 is a perspective view of a holder attachment having a discharge mouth.

Figure 6 is a perspective view of the holder attachment secured to a packing case.

Like numerals of reference indicate corresponding parts in the various figures.

40 Referring to the drawing, the holder as indicated in Figures 1 to 3 is shown in the form of a display case as indicated by the numeral 10, and having the central partition 11 which divides the casing into the two sections 12 and 13. These 45 two sections have their outer covers 14 and 15 in the form of glass, screening, netting, grate, lattice or other similar facing and are secured to the casing by means of the straps 16 which are secured either to the front or rear facings 14 and 50 15 thereby connecting the two covers simultaneously to the casing and in this way it will be noted that several kinds of edibles may be displayed in the case at the same time, such as for example, oranges and apples.

55 The holder attachment is formed of a frame

18 having a grated or other facing 19 and the straps 20. This holder attachment is adapted to be secured to the open section of a crate or case 21 by means of the straps 20 or other fastening members and in certain cases may have the 60 discharge member 22 connected thereto at the bottom or the holder itself may be constructed to have the discharge member form an integral part of the attachment.

In the use of the holder attachment, when it 65 is desired to apply the attachment to a crate or case as for example, in an orange crate, one side of the orange crate is removed and the attachment is secured to the open side of the crate by means of the straps or other fastening members 70 and in the case where the discharge member forms a part of the attachment, the oranges will simply roll down into the discharge member to be picked up by the shopkeeper or other attendant, when necessary.

75 It is of course understood that the sizes and shapes of the holder or holder attachment may be varied according to the requirements and the facing of the holder may be changed according to the kind of goods with which it is to be used, 80 so long as such facing will not hide the contents of the case from the views of the passersby.

What we claim is:

A holder for edibles and general merchandise comprising a display case having a central partition dividing the case into front and rear compartments, grid covers adapted to close the open ends of said front and rear compartments and secured thereto by common strap members, and a suspension hook fastened to said case.

85 WILLIAM THOS. LEATHERDALE.

90 WILLIAM JAMIESON WILSON.

95

100

105

110